EXTENSION TABLE

Cedric E. Millspaugh, Westlake, Ohio, assignor to
 Union-National, Inc., Jamestown, N. Y., a corporation of New York

Application May 22, 1947, Serial No. 749,643

1 Claim. (Cl. 311—42)

1

This invention relates to improvements in extension tables and more particularly to the supporting structure therefor.

As is well known, extension tables were developed primarily for the purpose of making available, as required, tables having greater top area than those of the fixed or drop-leaf top. In the manufacture of an extension table it is desirable to so conceal the extension structure that, when the end sections are in retracted position, the table will have the appearance of a conventional fixed-top table, with or without drop leaves. Generally speaking, the supporting structure of extension tables consists of extendable slides that connect the separable leg and top sections. These slides, when extended, provide ledges on which to locate leaves intermediate the separated sections. To sustain any weight that might be placed on the intermediate leaves of an extended table, or prevent the central portion thereof from sagging or bowing, it has been the practice to provide comparatively large slide elements, or support a pair of the most central slide elements on an intermediate leg section. The use of slides as the sole support of the central portion of an extended table is generally found to be unsatisfactory, if not at first, in subsequent use. The reason for this is that the central portion of the table is required to sustain substantially as much weight as the leg-supported end sections, and with only slides as a support, the central portion tends to bow or sag. Thus, a table of this construction often presents a stretched, unattractive appearance. Provision of a central pair of legs undoubtedly came into use for the purpose of overcoming the objections mentioned above. However, the intermediate leg unit has a comparatively small area for attachment to an intermediate pair of slide elements and is, therefore, usually weak and unable to properly support the central portion of an extended table. Additionally, the central leg unit invariably becomes located nearer one table end than the other when the table is in extended position, thus giving a very unbalanced appearance to the entire structure.

The present invention has been developed for the purpose of providing an extension table in which such structure is employed as to provide adequate support for the central portion of an extended table through the use of parts that will not, whether the table is in extended or retracted position, detract from the design appearance and this, therefore, constitutes one of the more important objects.

It is another object of the invention to provide

2

supporting structure for the central portion of an extension table that, when the table is in retracted position, is concealed and the table as a whole, with the possible exception of the dividing line of the fixed top sections, gives the appearance of a table unequipped with extension structure.

Another important object of the invention lies in the provision of intermediate leg supports that are rigid with the end leg supports.

A further object of the invention lies in the provision of an intermediate two-leg support, one leg being secured to one end section and the other leg to the other end section; the pair of legs, when the table is retracted, giving the appearance, with the other supporting structure, of a rigid, non-extendable, six-legged table.

Other objects and advantages of the invention will be more fully understood from a consideration of the following specification, taken in conjunction with the accompanying drawings; and in which

Fig. 1 is a perspective view of a table in which one form of the invention is embodied, a central portion of the fixed top panels being broken away to disclose the location of certain structural details;

Fig. 2 is a top plan view of the table in retracted position, a central portion of the fixed top panels being broken away to disclose the separable leg structure;

Fig. 3 is a top plan view showing the table in partially extended position, parts of the fixed panels being broken away to show the position of the parts of the separable leg unit when the table is extended; and

Fig. 4 is an enlarged fragmentary perspective view, with parts broken away and in section, showing details of the separable central leg unit.

Referring more particularly to the drawings, the reference numeral 10 is employed to generally designate a table in which one form of the invention is embodied. The table, in the present disclosure, is one of the drop-leaf extension type and includes two end sections 11 and 12. A leaf 13 is hinged to one edge of top panel 14 of section 11, and a leaf 16 is hinged to one edge of top panel 17 of section 12. Neither the hinge structure for these leaves, nor the means by which they are sustained in raised position, is shown since they constitute no part of the invention. Each of the sections 11 and 12 includes a pair of legs 18 which extend generally transversely of the table from an upright, ornamental support 19. On the upper end of the support 19 is secured one-half 21 of a split bridge. Each part 21 of the bridge is

formed with a pair of steps 22 and 23 which, when the table is in retracted position, interfit substantially as shown in Fig. 2. Of course, the bridge sections 21 provide a supporting shelf for the extendable slides 24. One end element 26 of each slide is secured to one bridge part, and the other end element 27 secured to the other bridge part, the intervening elements being relatively movable into extended or retracted position substantially as shown. The top panels 14 and 17 are mounted on and secured to the fixed slide elements 26 and 27 in conventional manner. Depending from the under face of each top panel and joined to an edge of the split bridge, is the usual apron 28. Of course, this apron is split, as shown, in order that the identical parts may be separated as the sections 11 and 12 are separated when the table is extended into a position such as suggested in Fig. 3.

An intermediate pair of legs 29, together with an upstanding support 31, is also provided. However, this intermediate structure is split into identical halves and, thus, each leg 29 will mount one-half 32 of the support 31. The upper end 33 of each of the parts 32 is joined to a corresponding portion of the split bridge, substantially as shown. Since the portions 32 of the support are intended to so interfit as to give the appearance of one of the end supports 19 when the table is in retracted position, the meeting lines thereof will be stepped at 34. It will be apparent that when the support parts 32 are brought together (Fig. 2) they become aligned transversely of the table and appear as a solid member. Adjacent the vertical parting line, ornamental means in the form of rods 36 are provided for securing the legs 29 to corresponding portions of the legs 19 of each of the end supporting sections.

It will be noted that each half of the intermediate support 31 is permanently joined to one of the end sections through the split bridge 21 and one rod 36. Thus, each of the intermediate legs 29 and the corresponding upright portion 32 is rigid with its corresponding end section and provides a table support wherein the end supporting sections include a strong and rigid three-legged structure. Of course, since the third leg of each end section is located near the central portion of the table when extended and these legs extend from opposite sides, it is evident that the table is provided with adequate support for all normal usage.

Referring particularly to Fig. 2, it will be noted that when the table is in retracted position, all parts interfit. The two top panels 14 and 17 abut, and the stepped portions of the split bridge are also in abutment. Similarly, the vertically split supports 32 are in alignment transversely of the table and give the appearance of a solid intermediate support. In fact, unless the user of a table of this construction closely examined the

supporting structure, it would not be apparent that the intermediate pair of legs 29 served other than as a fixed mid-table support. However, when the table is extended, as shown in Fig. 3, each end section includes three rigidly joined supporting legs. This structure obviously not only increases the strength of the supporting end sections, but also provides adequate support intermediate the end legs for the central portion of the table.

Although applicant has shown and described only one form of the invention, it will be apparent that the particular arrangement of interfitting the separable parts of the table supporting structure, as well as the spacing of the single leg with respect to the corresponding end legs, may be modified as required for tables of proportions different from those shown and described, without departing from the spirit and scope of the invention as set out in the annexed claim.

Having thus set forth my invention, what I claim as new and for which I desire protection by Letters Patent is:

In an extension table having a pair of separable end sections, an extendable slide joined to and facilitating adjustment of said sections into relatively extended or retracted position, a supporting structure for each section comprising an upright, a pair of legs joined to each upright, an intermediate upright, said intermediate upright being formed from duplicate parts and including interfittable ends, a leg joined to each part, the leg of one part extending in a direction opposite to that of the leg of the other part, said parts, when said sections are in retracted position, cooperating to provide an intermediate upright having the appearance and proportions of the upright for each of said sections.

CEDRIC E. MILLSPAUGH.
